CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a first embodiment of a design for a display screen or portion thereof with graphical user interface;

FIG. 2 is a front view of a second embodiment of a design for a display screen or portion thereof with graphical user interface;

FIG. 3 is a front view of a third embodiment of a design for a display screen or portion thereof with graphical user interface; and,

FIG. 4 is a front view of a fourth embodiment of a design for a display screen or portion thereof with graphical user interface.

The line dot line showing of a display screen or portion thereof, form no part of the claimed design. The text and other elements shown in dashed line form no part of the claimed design. All other text, numerals and other elements, excluding those shown in dotted line, are part of the claimed design.
